UNITED STATES PATENT OFFICE.

WILLIAM C. WADDELL, OF CLEVELAND, OHIO, ASSIGNEE TO HOYNES SAFETY POWDER COMPANY, OF CLEVELAND, OHIO, A CORPORATION OF DELAWARE.

METHOD OF MANUFACTURING EXPLOSIVE COMPOUNDS.

1,105,864.

Specification of Letters Patent.

Patented Aug. 4, 1914.

No Drawing.

Application filed June 27, 1913. Serial No. 776,068.

To all whom it may concern:

Be it known that I, WILLIAM C. WADDELL, citizen of the United States, residing at Cleveland, in the county of Cuyahoga and State of Ohio, have invented certain new and useful Improvements in Methods of Manufacturing Explosive Compounds, of which the following is a specification.

The invention set forth herein has reference to a new and original method of manufacturing explosives or explosive compounds, and the object of the invention is to produce an explosive or powder in spherical units or bodies of substantially spherical or rounded shape and of practically uniform size and density. To these ends the invention proceeds with certain steps and by the use of certain means which in themselves are simple and easily supplied and produce a built up unit as hereinafter described. Thus, as means or a medium in which the process or method may be performed, I may mention an ordinary wash tub or a tub especially constructed for the purpose but substantially like a wash tub in the main, though of a larger size, say three or four feet across and approximately sixteen inches deep and set at an inclination backward upon a central axis on which it is adapted to be rotated and tilted. This forms something of a trough shaped run or race in the angle of the tub between side and bottom in which all the work is done, and either hand or power may be employed to rotate the tub at the requisite rate of speed, say thirty revolutions to the minute. An apparatus of this type and particularly adapted for this purpose is disclosed and claimed in my copending application Serial No. 780,218, filed July 21, 1913. No other or further means than these are required except such as are used to supply the explosive ingredients to the tub. These begin with what are properly the nuclei of the powder units, a number or quantity of grains or granules of the powder of a relatively small size, say the size of small bird shot, although such grains or granules are

not necessarily round or spherical to begin with. Of course, a spherical shape would be preferable, but as a rule it is not practicable to get the nuclei in this shape, and I depend on their tendency to become round as the manufacture proceeds and particularly as an effect of their rolling after initial dusting and moistening has begun. The nuclei must of course be firm enough to maintain their individuality and not break down nor amalgamate as they develop or grow into complete units of the desired shape and size as the manufacture proceeds. Such nuclei may be specially made to begin with, but thereafter the manufacture of the pellets will supply them in abundance, as hereinafter fully described. The requisite quantity or number of nuclei having been placed in the tub and the rotation of the tub begun the work proceeds progressively and constructively with the said nuclei as the base, pulveriform explosive being supplied as hereinafter indicated. The proportion of the nuclei to the ultimate or finished product may be about as one to sixteen for pellets of a popular size. That is, each nucleus is supposed to build up or grow to about sixteen times its own original size or, if the measure be by weight, one pound of nuclei will make say sixteen pounds of finished powder. Of course these figures are suggestive rather than arbitrary because the demands of the market will be the determining factor as to size and quality, and any size can be supplied. In fact it is one of the chief advantages of this method of manufacture that the product can be furnished in any useful size according to the work for which it is intended.

For the present, and having placed the nuclei in the forming vessel or medium, referred to herein as a tub and having started the rotation of the tub, the next step is to dust the nuclei which are substantially dry with dustlike explosive of the same composition and then spray or mist in moistening liquid as the manufacture in hand may

require. In some instances I may use only pure water as the moistening liquid and in others a suitable solution comprising essential constituents of the powder, and if a binder be employed it usually is applied in this way, but not necessarily. However, all the ingredients of the powder are supplied in the liquid and the dry or dust form, and both are necessary to this process of manufacture and follow each other alternately. The first step necessarily is the application of the dust to the nuclei, and this order is necessary because the nuclei being small will blend if moistened first, and as the moistening occurs the pellets absorb what they need and naturally take on the dust and the rounded shape. A fairly fine hand sprayer will serve this purpose but, of course, for larger manufacture I employ sprayers under power pressure or head and dusters arranged in or about the face of the tub with means to liberate the dust as hereinafter described.

An experienced eye will readily detect when the pellets are ready for either application and also the quantity of each required. The operation proceeds by rolling and tumbling the pellets continuously, and as the tub revolves they are of course carried up its side a greater or less distance until they fall back by their own gravity and roll and tumble to the bottom. Of course they are not expected to become bunched or massed in this operation because they must not be moistened enough for this to occur and must maintain their individuality and build up as separate and independent units. The total effect of this mode of manufacture is to pack the pellets firmly as the growth proceeds, until at last, say about in twenty minutes, the nuclei shall have grown into pellets or spheres of the desired size. The tub is then emptied of its contents and another batch of nuclei placed therein and the work is resumed as before, and so on repeatedly. A single tub of the average size can readily turn out five hundred pounds of the finished product in about ten hours, and a battery of several tubs can be supervised by a single person, assuming of course that the actual work is mostly done by power.

Incidental or auxiliary to the foregoing manufacture of powder pellets or units in rounded or spherical shape—I have found that I can also make a quantity of granular powder in the same operation. Of course the latter is really a by-product of the manufacture of the pellets, but it is none the less an important and material product in a plant where both kinds of powder are produced, and particularly since it is very difficult to granulate some powders in large quantities. In this manufacture the spray or mist naturally falls more or less along the sides or borders of the comparatively

narrow space where the pellets roll and tumble as well as directly thereon, and as these borders or zones also receive more or less moisture and dust alternately and build up a crust, it follows that by the time several batches of pellets have been turned out the side accumulations are such that they require removal. These accumulations are sufficiently compacted to make good granules when dried, and when broken up I am enabled to sift therefrom all the nuclei required for continued manufacture as well as to store away a considerable quantity of granulated powder for outside blasting purposes. The said by-product is therefore valuable in itself and has the important advantage of being self productive and involving no expense of manufacture. It follows that I thus am enabled to make both spherical and granulated powder at the same time and in the same vessel and each as a separate and distinct article complete in itself and practically ready for the market.

When the pellets have been removed from the machine they are of such firmness that they can be poured onto the driers, whence they go to a separator to be assorted in sizes. The entire operation need not exceed a few hours from the tub to the dried and assorted article ready for the cartridge, if artificial drying be employed.

The pellets or spheres manufactured by this process are homogeneous and have the same quality and density in themselves from center to circumference and as compared one with the other. It is material in this manufacture that the nuclei when placed in the run way should at least be of such dryness as not to adhere one to the other, and hence I have found it necessary to first apply a suitable quantity of the powder dust and then administer a light spraying. The nuclei readily lay hold of the dust under these conditions and build up instead of falling down or blending, as they will if the operation be reversed. By "powder dust" I mean any one or more of the explosive constituents or ingredients mixed and reduced to a finely divided or dust state, and the finer the better for this purpose.

What I claim is:

1. The process of forming spherical explosive units or pellets which comprises keeping nuclei of explosive material in tumbling motion with successive additions of pulverulent explosive material of the same nature and of a moistening liquid until spherical bodies form by accretion, the additions of pulverulent explosive in each case being prior to the addition of said moistening fluid.

2. In the manufacture of substantially spherical explosive units or pellets, the process which comprises tumbling substantially dry nuclei of explosive material in the pres-

ence of dust like explosive of the same nature, adding a small proportion of moistening liquid and continuing the tumbling, and successively adding more dustlike explosive followed by moistening fluid until said nuclei by accretion have formed substantially spherical units of the size desired.

In testimony whereof I affix my signature in presence of two witnesses.

WILLIAM C. WADDELL.
